UNITED STATES PATENT OFFICE.

ANTHONY J. SCHROEDER, OF DONALDSONVILLE, LOUISIANA.

ROCKING-CHAIR FAN ATTACHMENT.

1,241,670.

Specification of Letters Patent.

Patented Oct. 2, 1917.

Application filed April 10, 1916. Serial No. 90,135.

To all whom it may concern:

Be it known that I, ANTHONY J. SCHROEDER, a citizen of the United States, and a resident of the city of Donaldsonville, in the parish of Ascension and State of Louisiana, have invented certain new and useful Improvements in Rocking-Chair Fan Attachments; and I do hereby declare that the following is a full, clear, and exact description of the same, reference being had to the accompanying drawings, and to the numerals of reference marked thereon, which form a part of this specification.

This invention relates to an improved attachment for rocking chairs and other objects which are capable of a reciprocating movement whereby the attachment is caused to be driven due to such movement taking place. It is the purpose of this invention to apply the reciprocating movement of an object to operate driving means for a fan mechanism whereby a current of air may be set up and by the circulation of air thus obtained, a cooling effect gained.

It is an object therefore of this invention to construct an attachment for connection upon a rocking chair, cradle, or other reciprocating object whereby the movements of the object are transferred to driving mechanisms which in turn drive, through flexible shaft connections, a ball bearing fan mounted in a convenient and adjustable position to obtain a current or flow of air.

It is also an object of this invention to construct a driving mechanism adapted for connection to an oscillating or reciprocating object to receive movement therefrom and to transform such movement into a continuous movement in one direction to drive an auxiliary apparatus, such as a fan.

It is finally an object of this invention to construct an attachment adapted for connection to a reciprocating object to utilize the movement thereof in transferring the movement to an auxiliary mechanism for any purpose whatsoever.

The invention (in a preferred form) is illustrated in the drawings and hereinafter more fully described.

50 In the drawings:

Figure 1 is a side elevation of a device embodying the principles of my invention attached upon a rocking chair and illustrating the operation in dotted lines.

55 Fig. 2 is a vertical transverse sectional view of the device with parts omitted, con-

nected on the curved rocker of the chair shown in section.

Fig. 3 is a horizontal sectional view of the lower portion of the device attached upon 60 the curved rocker of the chair.

Fig. 4 is a sectional detail illustrating in side elevation the interior mechanisms of the device.

Fig. 5 is an enlarged detail view with 65 parts broken away and parts shown in section, illustrating the adjustable mounting for a fan adapted to be driven by the attachment device.

Fig. 6 is a sectional detail view illustrating the bearings and clutch for the fan.

Fig. 7 is a detail of the roller clutch taken on line 7—7 of Fig. 6.

Fig. 8 is a similar view of another roller release clutch used in another part of the 75 mechanism.

Fig. 9 is a detail view of the means for retaining the flexible shaft leading to the fan connected to the driving means.

Fig. 10 is a fragmentary top plan view 80 with parts shown in section, of the upper portion of the device.

Fig. 11 is an interior view of a modified form of device.

Fig. 12 is a top plan view of the mechanisms shown in Fig. 11, with parts broken away and shown in section, and parts omitted.

Fig. 13 is a sectional detail view illustrating an end elevation of the driving 90 mechanisms at the upper end of the structure shown in Fig. 12.

As shown in the drawings:

The reference numeral 1, indicates as a 95 whole a rocking chair, the rockers of which are denoted by the reference numerals 2. The device for attachment to a rocker consists of a rectangular base frame 3, as clearly shown in Fig. 3, and mounted on one side thereof, as clearly shown in Fig. 2, are 100 laterally extending attachment bolts 4, provided with wing nuts 5, on each of which U-shaped clamping straps 6, are mounted, adapted to be clamped upon one of the rockers when the wing nuts 5, are tightened. 105 Secured at each end in the rectangular frame 3, are pivot shafts or rods 7 and 8, shown in Fig. 4, and journaled on each thereof are long actuating levers 9 and 10, respectively, each having an integral hub 110 portion which fits around its pivot shaft. The outer ends of each of the actuating

levers 9 and 10, are of yoke shape and journaled therein are small wheels or rollers 11 and 12, respectively, which normally contact with the floor.

5 Secured to the rectangular frame 3, and extending upwardly therefrom is a sheet metal housing, denoted as a whole by the reference numeral 13, and as clearly shown in Fig. 1, of substantially trapezoidal shape in side elevation, and having an upper removable arched cover member 14. Secured rigidly within the upper end of the housing 13, and as well affording a brace therefor, is a small rectangular frame 15, shown in detail in Fig. 10, and mounted transversely thereof is a shaft 16. Journaled on said shaft 16, is a sleeve 17, having a central toothed clutch portion or spider 18, forming a part of a double clutch mechanism, and journaled 10 upon said shaft 16, near one end thereof is a large gear 19, having a jaw clutch connection 20, with said sleeve 17, whereby said gear 19, may be driven thereby. Journaled 15 on one end of the sleeve 17, is a drum 23, and on the other end thereof is another drum 24, the inner flanges of each of said drums being increased in diameter and flanged toward one another, as clearly shown in Fig. 10, bearing against a separator ring 25, disposed around the double clutch element 18. Said double clutch element 18, is provided with a series of teeth, as clearly 20 shown in Fig. 8, disposed on each side of the separator ring 25, and each provided 25 with a series of rollers 26, adapted to co-act with the inwardly flanged portions of the respective drums 23 and 24, whereby each of said drums is capable of transmitting a drive through said rollers to the clutch element 18, in one direction, yet permitting the clutch element 18, to over-run either of the respective drums 23 and 24.

30 Journaled at one end of the small rectangular frame 15, is a pinion 27, meshing with the gear 19, to be driven thereby, and connected to be driven by said pinion is one element 28, of a jaw clutch, the other element 29, of said jaw clutch being removable therefrom, though held engaged therewith by insertion through a sleeve 30, provided on said frame 15, and by a curved pivoted retaining arm 31, normally impelled into engaging position by a spring 32, engaging in a groove provided in the outer end of said 35 clutch element. The outer end of said clutch element 29, is connected in any suitable manner to a flexible shaft 33, leading through a flexible tube 34, which in turn leads to an upright rigid bracket tube 35, held by means of clamps 36, upon the arm of the rocking chair 1. Adjusting bolts 37 and 38, are provided for said clamping arms 36, to hold the same in clamping relation upon the arm of the rocker and also permit 40 of vertical as well as rotational adjustment

of the upright 35. An adjustable bracket 39, is provided at the upper end of the upright 35, carrying a sleeve 39', shown in detail in Fig. 6, for a fan shaft 40, to which the end of the flexible shaft 33, is connected. Journaled 45 on the outer end of said fan shaft 40, is a propeller fan 41, having a hub member 42, forming a part thereof, which projects inwardly and sustains the weight of the fan upon ball bearings 43, the race for which is afforded 50 by a cylindrical member 44, which extends into the sleeve 39', and is rigidly secured therein. A ball clutch connection is provided between the shaft 40, and the hub member 42, to drive the fan, as shown in detail in Fig. 7, said shaft 40, for this purpose having fixed thereto a spider 45, rotating within the hub member and provided with a series of rollers 46, adapted when said spider is rotated in one direction to 55 wedge the rollers into contact with the inner periphery of the member 42, to thereby drive the fan.

The driving connection between the actuating levers 9 and 10, by which the rocking 60 movement of the rocker is transmitted as rotational movement to the drums 23 and 24, is provided by cords or cables 47 and 48, respectively. One end of the cable 47, is attached to the end of the actuating lever 9, and wound with a few turns around the drum 23, and then led downwardly and connected to the outer end of the actuating lever 10, and the other cord 48, is connected 65 at the same point on the actuating lever 10, as the last mentioned cord 47, and is led upwardly and around the drum 24, and downwardly to the same point on the outer end of the actuating lever 9, as the first mentioned cord 47.

In the modified form of my invention illustrated in Figs. 11, 12, and 13, I have utilized actuating levers 49 and 50, respectively, having small wheels or rollers 51 and 52, journaled in the outer ends thereof. Said actuating levers 49 and 50, are pivotally mounted somewhat as described with reference to the actuating levers 9 and 10, and at their inner ends have formed integral therewith gear segments 53 and 54, respectively, the latter meshing with a small pinion 56, and the former meshing with a small idler pinion 55, which in turn meshes with a pinion 57. Thus a downward movement of the gear segment 53, will transmit movement through the idler pinion 55, in one direction to the pinion 57, and a downward movement of the segment 54, will likewise transmit a similar direction of movement directly to said pinion 56. The pinions 56 and 57, are mounted upon a shaft 58, which extends transversely through bearings provided in the framework of the structure, and are each operatively associated with one member of a double clutch mechanism.

This double clutch mechanism is denoted respectively by the reference numerals 59 and 60, and is adapted to transmit movement in a manner similar to the double 5 clutch mechanism 18—23—24, to a large driving gear 61, journaled on the shaft. The driving gear 61, meshes with a small pinion 62, which has releasable clutch engagement by means of a clutch 63, with a 10 flexible shaft 64, which leads upwardly to drive a fan as in the construction previously described.

The operation is as follows:

The device is clamped upon one of the 15 rockers 2, of the rocking chair, as shown in Figs. 1, 2, and 3, by means of the clamps 6, provided for the purpose. As a result, when the rocking chair is caused to oscillate through the dotted line positions shown in 20 Fig. 1, the frame of the attachment will be moved therewith, thus causing relative movement between the frame of the attachment and the actuating levers 9 and 10, on which the rollers 11 and 12, are mounted, to 25 take place. The relative oscillating movement between the frame of the device and the actuating levers 9 and 10, causes the cords 47 and 48, to rotate the respective drums 23 and 24, whereby, through the 30 clutch mechanisms provided, said drums act to transmit a continuous movement of rotation to the driving gear 19. The drive from the gear 19, is of course transmitted from the small pinion 27, to the flexible shaft 35 which leads upwardly to the fan 41, and serves to drive the same through the ball clutch mechanism 45—46. The fan may be adjusted to any position to direct a current of air, as desired, by adjustment of the 40 upright member 35, in the bracket 36, and also by adjustment of the bearing bracket 39.

In the modified form of my device illustrated in Figs. 11, 12, and 13, the operation is identical with the exception that the drive 45 from the actuating levers 49 and 50, provided, is slightly different in that the gear segments 53 and 54, respectively, formed thereon, serve to drive pinions, which in turn drive a main driving gear 61, through 50 clutch mechanisms 59 and 60. The arrangement of the gear mechanisms and clutches, however, is such that the same direction of rotation always is imparted to the gear 61, irrespective from which one of the levers 55 49 or 50, the drive is received, due to oscillating movements of the frame of the device with respect to said actuating levers.

I am aware that various details of con-

struction may be varied through a wide range without departing from the principles of this invention, and I therefore do not purpose limiting the patent granted otherwise than necessitated by the prior art.

I claim as my invention:

1. The combination with a rocking chair, 65 of a fan attachment therefor, comprising a housing adapted to be secured rigidly to the rocking chair, actuating levers pivotally mounted therein with their ends projecting in opposite directions therefrom, means on 70 the ends thereof for contact with the floor, a driving gear, clutch mechanisms interposed between said driving gear and levers whereby rotation of said gear in one direction only is effected by the movement of said 75 levers, a fan mounted upon the rocking chair, and flexible driving connections between said fan and said gear.

2. The combination with a rocking chair, 80 of a fan attachment therefor comprising a housing adapted to be secured rigidly to the rocking chair, actuating levers pivotally mounted therein with their ends projecting in opposite directions therefrom, means on 85 the ends thereof for contact with the floor, drums mounted within said housing, cables wound around said drums and each connected to the inner ends of both of said actuating levers, a driving gear, clutch mechanisms interposed between said driving 90 gear and drums whereby rotation of said gear in one direction only is effected by the movement of said drums, a fan mounted upon the rocking chair, and flexible driving connections between said fan and said gear. 95

3. The combination with a rocking chair, 100 of a fan attachment, comprising a pair of actuating levers, cables connected thereto, drums around which said cables are wound, a driving gear, clutch mechanisms interposed between said drums and said driving gear whereby said gear is driven in one direction by said drums driven by the cables, a pinion operated by said driving gear, a 105 flexible shaft connected to said pinion, a fan adjustably mounted upon the rocking chair, and clutch mechanisms interposed between said flexible driving shaft and said fan whereby the fan is driven thereby.

In testimony whereof I have hereunto 110 subscribed my name in the presence of two subscribing witnesses.

ANTHONY J. SCHROEDER.
